FRANK KOGL, OF ST. PAUL, MINNESOTA, ASSIGNOR OF ONE-HALF TO HANS STEINGAS-SINGER, OF ZELL-ON-THE-ZILLER, AUSTRIA

LIFE PRESERVING DEVICE

Application filed May 26, 1930. Serial No. 455,653.

This invention relates to life preserving apparatuses, and the primary object is to provide a mechanism, for attachment to any suitable form of pneumatic life preserving unit, which mechanism will generate gas to inflate the unit so that the unit can be carried about or normally kept in a collapsed condition until there is occasion to use it, at which time the generating mechanism is put into action to inflate the preserver proper, thus effecting an economy in space when the device is not in use. Further and more detailed objects will be disclosed in the course of the following specification, reference being had 10 to the accompanying drawings, in which:

Fig. 1 is a diametrical sectional elevation of my improved generator unit, showing it as attached to a pneumatic life preserver.

Fig. 2 is a cross sectional view as on the line 2—2 in Fig. 1.

Fig. 3 is a top end view of the generator.

Referring to the drawings more particularly and by reference characters A designates generally a pneumatic or inflatable life preserver unit, which may be of any suitable size, form, or design, and is attached to the nipple 4 of the generator as shown in Fig. 1 so as to be in communication therewith.

The generator proper comprises a cylinder 5 having a cap 6 screwed upon one end while its opposite or lower end is threaded to screw tightly into the flange 7 of a cup shaped chamber 8, a gasket 9 being preferably inserted in the joint to insure sealing contact.

The cylinder 5 is provided in its lower end with an annular arcuately curved partition 10 that continues in a trunco-conical valve seat 11, which, in turn is again joined to the cylinder body by a flat, integral cross wall 40 or partition 12. Thus the lower end of the cylinder combines with the integral members 10—11—12 to form an annular passageway 13, with which the nipple 4 connects, while the members 6, 5, and 10 unite to form a 45 relatively large water chamber 14 that is normally closed by a valve core 15 fitting in the seat 11.

The valve 15 is secured upon the lower end of a rod 16 by nuts 17 and 18 which are adjustable so that the valve may be adjusted

longitudinally on the rod if and when necessary. The upper end of the rod is slidable in a bushing 19, of the cap 6, and has a small cross pin 20, at its upper extremity, which operates in a pair of cam acting slots 21 in a pair of disk members 22. The members 22 are rotatably secured to the cap 6 by a pair of straps 23, and are both integrally joined by a lever member 24. It will thus be seen that when the lever is down, as shown, the cam disks will operate to hold the valve 15 closed, but when the lever is tripped or moved upwardly the cam slots 21 will act upon the pin 20 to move the rod 16 downwardly, thus opening the valve 15 to permit the water in chamber 14 to flow down into the chamber 8.

The above noted downward movement of the rod 16 also operates to open communication between the chambers 13 and 8, as follows: The horizontal partition 12 is provided with an annular series of perforations 25 that are normally closed by the ring shaped flange 26 of a spider or disk 27 having openings 28. This disk is attached to the rod 16 between the valve 15 and nut 18, and consequently when the valve is opened the flange 26 separates from the partition 12 so that communication between chambers 8 and 13 is established through the perforations 25 and 28. Closing of the valve 15, by the lever 24, 80 also of course closes the flange 26 against the perforations 25.

The chamber 8 is employed for the purpose of storing a supply of gas producing material such as calcium carbide, designated 85 as 29, which when charged with water will generate a substantial volume of acetylene gas, or such other gas as the particular generating material may throw off. The material 29 is preferably held in place by a coarse screen 30 detachably secured by a split ring 31 which is sprung outwardly into a small annular groove in the inner surface of the cup 8.

The operation of the device may be briefly set forth as follows:

When the device is to be carried on the person or otherwise kept in readiness for emergency use, the chamber 14 is filled with water, the cup 8 is filled with a carbide or other gas generating material, the lever 24 is down, and

the preserver float A is deflated. When the operator then anticipates use for the device, or even if he finds himself thrown into the water, he has but to release the lever 24, which 5 action will open the valve 15 and the ports 25. The water in chamber 14 then escapes into the chamber 8 where it contacts with the carbides 29 and generates the desired gas and as such gas is rapidly generated it escapes through 10 the openings 28, 25, 13, and 4 to the preserver unit and thus inflates the latter so as to buoy up and support the person wearing or holding the device.

It may here be noted that the invention 15 also contemplates broadly the idea of providing a generator wherein the carbide is so arranged that it will permit water to enter from outside of the unit, thus automatically starting the generation of gas should the bearer 20 fall into the water, and such a device may also of course have a water chamber so that the generation may be manually started.

It is understood that suitable modifications 25 may be made in the structure as disclosed, provided such modifications come within the spirit and scope of the appended claims.

Having now therefore fully illustrated and described my invention, what I claim to be new and desire to protect by Letters Patent is: 30 1. A generator for life preservers comprising a cylinder having a water chamber therein, a container for carbide or the like attached to the cylinder, a valve normally closing the water chamber and which when 35 opened will permit water to flow into the container, said cylinder having an annular passageway about the valve for communication with the preserver, and valve controlled means normally closing the passageway with 40 respect to the container.

2. A generator for life preservers comprising a cylinder having a water chamber therein, a partitioning member in one end of the cylinder forming an annular passageway, communicating with the preserver, and a central valve seat, a container attached to said end of the cylinder for carbide or the like, a valve core associated with said seat to open the water chamber to the container, 50 and means operative by movement of the valve core to establish communication between the container and the said passageway.

3. A generator for life preservers comprising a cylinder having a water chamber therein, a partitioning member in one end of the cylinder forming an annular passageway and a central valve seat, a valve head associated with said seat, and a valve for closing 60 communication between the annular passageway and the container.

4. A generator for life preservers comprising a cylinder having a water chamber therein, a partitioning member in one end of the cylinder forming an annular passageway

and a central valve seat, a valve head associated with said seat, and a valve for closing communication between the annular passageway and the container, said container having a screen for retaining the carbide 70 therein.

5. A generator for life preservers comprising a cylinder having a water chamber therein, a partitioning member in one end of the cylinder forming an annular passageway 75 and a central valve seat, a valve head associated with said seat, and a valve for closing communication between the annular passageway and the container, said container having a screen for retaining the carbide 80 therein, and means for simultaneously opening both of said valves.

6. A generator for life preservers comprising a cylinder having a water chamber therein, a partition member in one end of the cylinder forming an annular passageway and a valve seat, a container attached to said end of the cylinder, and adapted to communicate with the passageway through perforations in the partition member, a valve for the valve 90 seat and a valve for normally closing the perforations, and a manually operated rod extending axially of the cylinder for opening both of said valves.

Signed at Minneapolis, Minnesota, this 95
24th day of May, 1930.

FRANK KOGL.
